UNITED STATES PATENT OFFICE.

CHARLES F. PAPE, OF HYDE PARK, PENNSYLVANIA, ASSIGNOR TO HUTCHINS CAR ROOFING COMPANY, OF DETROIT, MICHIGAN, A CORPORATION OF MICHIGAN.

CAR-ROOF.

1,122,414.

Specification of Letters Patent. Patented Dec. 29, 1914.

Application filed September 12, 1910, Serial No. 581,573.

To all whom it may concern:

Be it known that I, CHARLES F. PAPE, a citizen of the United States of America, residing at Hyde Park, in the county of Westmoreland and State of Pennsylvania, have invented certain new and useful Improvements in Car-Roofs, of which the following is a specification, reference being had therein to the accompanying drawings.

10 The invention relates to car roofs of the type having flanged metallic roofing plates and weather proofing caps, and the invention consists in the construction as herein-after set forth.

15 In the drawings,—Figure 1 is a perspective view of a portion of the car roof embodying my invention; Fig. 2 is a cross-section through the ridge cap; Fig. 3 is a plan view partly in horizontal section.

20 A are metallic roofing sheets arranged in series upon the roof frame and provided at the ridge with an upstanding flange B, at the eaves with a depending flange C and upon their opposite sides with upstanding flanges F.

25 G are weather caps which embrace the upstanding side flanges of the adjacent sheets and extending from the ridge to the eaves, and H is a ridge cap which embraces the upstanding flanges B. It is usual to secure the roofing plates at the eaves by nailing them to the sides of the car or by other suitable means, while the sheets at all other points are permitted a limited 30 freedom of adjustment on the roof frame, thereby avoiding distortion. It is however, necessary to secure the weather caps to the roof structure, which is usually accomplished by bolts arranged at the ridge.

35 Thus, the ridge cap is necessarily given a considerable degree of strength and rigidity, but in constructions that have heretofore been used this strength has not been utilized for the performance of any mechanical function other than the holding of the cap in position.

40 It is the object of the present invention to make use of this ridge cap for the securing of the roofing sheets and thereby to avoid the necessity of securing said sheets at the eaves.

45 It is a further object to obtain a simple and inexpensive construction to manufacture and assemble.

50 To accomplish the purpose of the inven-

tion, the upstanding flanges B on the sheets A are engaged with the ridge cap H so as to be retained by the latter from movement toward the eaves. The caps H are preferably bent inwardly at I to form an engaging bearing for the flanges B near the center of each sheet, thereby permitting the sheets a limited angular or pivotal adjustment in relation to the cap. The caps G which engage the side flanges of the sheets provide the necessary clearance for the angular movement of the latter. These caps G at the point of juncture of the ridge cap are protected by junction caps J which are secured by bolts K to the ridge purlins of the roof structure. The bolt K also preferably engages an aperture flange on the cap G so that the latter is also secured at the ridge. At the eaves the cap G may be secured by a bolt L but the plates A are preferably free to adjust themselves and are not secured by nails or other rigid securing device. Thus, while the sheets are held down through the caps G they are permitted universal freedom of adjustment.

55 What I claim as my invention is:

1. In a car roof, the combination with a roof frame, of a metallic roofing sheet having an upstanding flange at the ridge, upstanding flanges at opposite sides and a 60 depending flange at the eaves, a weather cap embracing the upstanding side flange of said sheet forming a means of holding the latter down upon the roof frame, and a ridge weather cap embracing the upstanding flange of said plate at the ridge and pivotally engaging a central portion of the same to hold said plate from outward movement.

2. In a car roof, the combination with a 65 roof frame, of a metallic roofing plate supported thereon and having upstanding flanges at opposite sides and the ridge, and a depending flange at the eaves, a weather guard cap embracing the upstanding side flange of said plate, and a ridge 70 weather guard cap embracing the ridge upstanding flange and mechanically engaging the same, said mechanical engagement being at the central portion only and forming the sole positive means for limiting said plate 75 from outward movement on the roof frame.

3. In a car roof, the combination with a 80 roof frame, of a series of metallic roofing plates supported on said frame provided with upstanding flanges at their sides and 85

at the ridge, and a depending flange at the eaves, weather caps embracing adjacent upstanding side flanges, a ridge cap embracing the upstanding ridge flange and mechanically engaging the same, said engagement being located at the center of the sheet to provide a limited pivotal adjustment of the sheet with said engagement as the point of pivot.

10 4. In a car roof, the combination with a roof frame, of a metallic roofing sheet supported thereon having an upstanding flange at the ridge, and a ridge weather proofing cap embracing said upstanding flange and mechanically engaging a limited portion thereof intermediate the ends for pivotally securing said sheet.

15 5. In a car roof, the combination with a roof frame, of a metallic roof sheet supported thereon and a ridge cap forming a weather guard for the upper edge of said

sheet, said ridge cap having a central portion of lesser width than the upper edge of the sheet engaging said sheet and forming a pivotal securing means therefor.

25

6. In a car roof, the combination with a roof frame of a metallic roof sheet supported thereon, and a ridge weather proofing cap forming a weather guard for the upper edge of said sheet, a portion of said weather guard of lesser length than the upper edge of the sheet having an engagement with said upper edge of the sheet, said sheet being adapted to have a limited adjustment around the said engaging portions as a point 30 of pivot.

35 It testimony whereof I affix my signature in presence of two witnesses.

CHAS. F. PAPE.
